UNITED STATES PATENT OFFICE

JOHN B. CAMPBELL, OF SALEM, NEW JERSEY, ASSIGNOR, BY MESNE ASSIGNMENTS, TO CARTHAGE MILLS INCORPORATED, OF CINCINNATI, OHIO, A CORPORATION OF OHIO

FLOOR COVERING

Application filed June 7, 1926. Serial No. 114,062.

My present invention relates to floor coverings, and has particular reference to a floor covering which has the characteristics of ordinary carpet to an enhanced degree, and coordinately, my invention relates to the method of manufacturing such a floor covering, and to the apparatus used.

Carpet generally has a woven base of coarse characteristics, such as burlap, the wearing surface of the carpet being provided by associating with the burlap, generally by weaving, certain piling which completely covers the burlap and which presents an ornamented or colored wearing surface.

It is one of the objects of the present invention to provide a floor covering wherein a carpet wearing surface is presented, offering an increased resistivity to wear.

Another object of my invention is the provision of a floor covering of laminated construction, comprising a pile fabric permanently associated with a layer of felt, so that the two form unitary parts of a floor covering.

It is a feature of my invention to employ a coarse woven material such as burlap, a finer woven material such as a pile fabric, and an intermediate layer of material which permits the association of the two woven materials in a manner which will produce a floor covering of an entirely novel character. More particularly, it is a feature of my invention to associate the top pile fabric with the lower coarse fabric by sandwiching therebetween a layer of relatively heavy base material, such as saturated felt, to the opposite faces of which the layers of woven material are secured.

I shall hereinafter describe and illustrate a floor covering wherein saturated felt is so used, but it will be understood that as to certain phases of my invention the employment of this particular type of base material is not essential.

It is another object of the invention to provide a floor covering which employs a wear-

ing surface comprising a fabric such terry weave, whereby numerous advantages are obtained.

It is a further object of my invention to accomplish these ends by a method of manufacture which is at one time expeditious and inexpensive.

In general, my invention contemplates the association of superposed layers of materials in such a manner that the characteristics of each are instrumental in producing the desirable final effects, while at the same time a unitary or integral structure is produced which is incapable of separation.

For the attainment of the foregoing objects and such other objects as may herein-after appear or be pointed out, I have illustrated one form of my invention in the accompanying drawings in which—

Fig. 1 is a cross-section through a completed floor covering which is illustrative of my invention; and

Fig. 2 is a diagrammatic representation of the apparatus which may be employed in its manufacture.

Referring to the drawings, it will be observed that I have associated a base layer 12 of burlap or similar coarse material, with a top layer 11 of relatively finer material, by the interpositioning or sandwiching of a layer of saturated felt 10. I prefer to utilize a material of the saturated felt type because of its numerous advantageous characteristics in connection with floor coverings. This type of material, as generally used in the manufacture of floor coverings such as oil cloth, is made from a pulped mass having a rag and paper content in proportions which depend upon the character of base desired. For example, a base containing equal parts of rag and paper is quite satisfactory. This pulped mass is rolled into sheets of any desired thickness, and it is generally saturated or impregnated with some such material as bitumen or asphalt, any excess of this material

being suitably squeezed out. A base of this character has body, and will tend to flatten out and cling to a floor; it is also waterproof, and acid and insect proof. Its use in the present manner is therefore particularly advantageous. It serves at one time as a suitable medium for associating the base of burlap with the top layer, as an element which imparts body and weight to the finished product, and as an insulator both as to water, 10 moths, or insects, between the burlap base which rests upon the floor and the pile fabric top which presents the wearing surface.

For the purpose of imparting to the completed article the desirable characteristics of true carpet, and additional advantages, I employ as the top layer a pile fabric 11, this fabric being bound to the base 10 by a suitable binder which will be described hereinafter. I have found that an uncut-pile fabric, such as a terry weave, embodies certain advantageous attributes which render it particularly adaptable to my present purpose. A fabric of this character comprises a base, 25 and piling associated therewith in a manner which presents an outer surface of uncut threads, or loops. An outer surface of this character has extremely high wearing qualities, due perhaps to the absence of any tendency for the piling to be worn away or loosened, and a fabric of this character is particularly adaptable for varied ornamentation. The association of a fabric of this character with a relatively heavy base material such as saturated felt, this association being of a character which provides a unitary 35 structure, is extremely advantageous in the carrying out of the present invention.

In a preferred method of carrying out the invention. I associate with the opposite side of the felt base 10 a second sheet of woven fabric, preferably of a rather coarse type such as burlap 12. This sheet is associated with the base fabric 10 in any desired or 45 suitable manner, and I prefer to utilize a binder which will permit the simultaneous association of both woven fabrics with the base material 10, during the manufacture of the floor covering. The fabric 12 imparts 50 strength to the finished product by preventing distortion thereof, and it also serves as an extremely satisfactory ground layer or base coating which has extremely good wearing qualities for this purpose.

Where I employ a saturated felt base 10, it will be understood that the binder which I subsequently employ may be constituted of the saturant itself. However, I prefer to apply a separate binder, and in this way I 60 am enabled to utilize a base 10 which has either been saturated or not saturated at some previous stage of manufacture. The base 10, when saturated, is generally impregnated with asphalt of low grade. The subsequent binder which I apply is preferably 65

comprised of asphalt of a relatively high grade. For example, it is desirable for this binder to have a melting point of approximately 180°, a temperature which is seldom attained during ordinary usage of the finished product. It is also desirable that the binder contain a minimum of free oil, and it is applied to the base 10 in a manner which will prevent subsequent injury to the ornamental outer fabric 11. More particularly, 75 it is preferable to apply the binder in a heated state and thereupon permit it to cool somewhat until its viscosity has been increased to a plastic but partially dry condition. When this condition has been reached, the woven fabric layers may be applied, and any tendency for the free oils of affect either of these layers has been minimized. This will be due to the fact that any free oil which may exist will have been absorbed by the felt base during the cooling, and due to the additional fact that the free oils are released only at 80 high temperatures.

In a preferred method of carrying out the invention, I lead the fabrics 11 and 12 in the form of continuous strips from rollers 13 and 14, and I lead the base material 10 in a similar state from a roller 15. These three continuous strips are eventually led into superposed position between a pair of pressure rollers 16, the base 10 being sandwiched between the woven fabrics at this time. During its course from the roller 15 to the roller 16, the strip 10 is made to pass through a binder bath 17 wherein it is coated on both sides with a binder 18 of the character hereinbefore described. After leaving this bath 17, the strip 10 is preferably made to pass between a pair of rollers 19 whose function 95 is to remove excess binding material 18. It will be obvious that pressure members or similar means may be employed in lieu of the rollers 19. For the purpose of permitting the binder 18 to dry partially, the rollers 16 are preferably set at a distance from the 100 rollers 19, and during the passage of the strip 10 from the bath 17 to the rollers 16, the binder 18 is placed into such condition that at the time of association of the three superposed layers of material no injurious effects 115 upon either of the woven fabrics will be produced.

During the passage of the three strips through the roller 16, they are mutually 120 squeezed or pressed together, and the binder will serve to bind them into one unitary structure. In this connection, it will be observed that the woven fabrics will permit of very close association with the base material, for the reason that the binder will work its way between the strands of the woven fabric and thereby serve in a very efficient manner. Moreover, this intimate association between the binder and the woven fabric will 125 securely anchor the pile threads, whether 130

they be cut or uncut, so that the finished product will have extremely good wearing qualities.

I have thus far specifically disclosed the use of a felt as the intermediate member for bonding the top and bottom layers 11 and 12 to each other because of the advantages obtainable by the use of such a material. I have, however, found that from the stand-
10 point of the production of a carpet having a maximum degree of flexibility without cracking, the use of a thin fabric, preferably a woven fabric such as is generally termed in the art "sheeting", presents advantages which
15 are not attainable where a felt of a weight and character generally used commercially, is employed. It will therefore be understood that my invention in its broader aspect involves generally the use as the intermediate
20 layer or member 10 of the class of material which includes within it sheeting as defined above, and also felt, and that in its more specific aspects, my invention involves the use as the intermediate layer either of a felt mate-
25 rial for the particular advantages which it presents or the use of a thin woven material for the advantages which such woven mate-
rial presents.

While I have described in this application
30 the use of asphalt as a binder, I do this as an exemplification of a binder which serves particularly in connection with the use of an asphalt saturated felt base. It will be understood, however, that the use of other type
35 binders, such as gums, glues or silica compounds, may be found more advisable, particularly in connection with the employment of sheeting as the intermediate member, and, in fact, it is not essential to my invention to em-
40 ploy even with asphalt saturated felt a binder of the type herein described as employed with that material.

It will be obvious that the top fabric may be suitably ornamented either before or after
45 its association with the other elements of the finished product. Similarly, although I have illustratively shown one method of carrying out my invention, and whereas I have indicated the general characteristics of apparatus
50 which may be used in carrying out my invention, nevertheless it will be well understood that many changes in the details herein described and illustrated may be made by those
55 skilled in the art without departing from the spirit and scope of the invention as expressed in the appended claims. It is therefore intended that these details be interpreted as illustrative and not in a limiting sense.

60 Having thus described my invention and illustrated its use, what I claim as new and desire to secure by Letters Patent is:

65 1. A floor covering comprising a ground layer of burlap, an intermediate layer of asphalt-saturated felt-base material, and a top

layer of terry cloth, said layers being bound together by a binder comprising asphalt.

2. A floor covering comprising a top layer of uncut pile fabric, a bottom layer of a coarse woven fabric, and an intermediate layer of
70 sheeting to which the other two are bonded.

3. A floor covering comprising a lower layer of asphalt-saturated felt-base material, and a top layer of uncut pile fabric, said layers being bound together by a binder comprising high grade asphalt.
75

In witness whereof, I have signed this specification this 3rd day of June, 1926.

JOHN B. CAMPBELL.
